UNITED STATES PATENT OFFICE.

PETER EDUARD GELDHOF, OF SYRACUSE, NEW YORK, ASSIGNOR, BY MESNE ASSIGNMENTS, TO UNITED STATES HOFFMAN MACHINERY CORPORATION, OF NEW YORK N. Y., A CORPORATION OF DELAWARE.

GARMENT PRESS.

Application filed February 2, 1921. Serial No. 441,931.

This invention relates to steam garment pressing machinery and especially to garment presses which are steam heated and which have a steam operated suction system 5 to dry and cool the garment. More particularly, the invention relates to improvements in piping systems for steam garment presses.

An object is to produce an improved piping system which performs the double purpose of supplying steam to heat the pressing members and which steam also produces the required suction, so that a garment press, such as shown in the Spencer Patent 1,326, 15 982, may be more efficiently operated; and in disclosing my invention I have omitted the upper movable pressing member known as the head.

The accompanying drawings form a part 20 hereof and are more or less diagrammatic in form, with all parts omitted which do not bear a close relation with the invention.

This piping system is connected with one or both of the pressing members of a steam 25 garment press, but in the drawings I have preferably shown only the bed or buck, or lower padded garment support 5, carried on a suitable frame 6. The bed is equipped with heating and suction means, and to 30 this end an interior steam heated chamber 7 and a suction chamber 8 are provided. A perforated face plate 9 forms one wall of the suction chamber 8, and in actual use this plate is covered with porous padding 35 as a yieldable support for the garments to be pressed.

A steam supply pipe 11 connects with the heating chamber 7 in the buck and is meant 40 to supply live hot steam thereto from any suitable source, such as a boiler. The steam circulates in the chamber 7, as indicated by the arrows, and gives up a portion of its heat thereto, whereby the temperature of the bed 5 is raised to adequately press garments. A steam discharge pipe 12 connects 45 with the heating chamber 7 and conveys the steam therefrom. The steam transmitted through the discharge pipe 12 in the direction of the arrows is employed to produce 50 a suction for evacuating air from the suction chamber 8; and to this end an ejector is connected to the discharge pipe 12.

The ejector tube comprises a pipe fitting 15, used as a casing, in which a pressure

discharge nozzle 16 is disposed and joined 55 to the discharge pipe 12 leading from the heating chamber 7 in the bed. A suction pipe 17 connects with the suction chamber 8 in the bed and the ejector fitting 15, and the arrangement is such that when steam 60 discharges under pressure from the nozzle 16, there is produced a suction of air downwardly through the pipe 17, which is blown out through the outer discharge pipe 18 along with the steam discharged from the 65 nozzle. A valve 19 is included in the discharge pipe 12 and placed between the ejector and bed and so arranged that when the garment press is not working this valve is closed, whereby no steam is discharged from 70 the bed through the ejector, nor is there any suction of air produced downwardly through the suction pipe 17.

In the operation of a steam garment press equipped with this piping system, the operator completes the steaming and pressing operation, as is known to those conversant in the art, and immediately thereafter to dry the garment he will open the valve 19 by any suitable means. The garment is left on the bed after the pressing operation so it may be dried by opening the valve 19, and when the operator opens this valve the suction produced as aforesaid creates a draft of air 80 downwardly through the garment resting 85 on the padding and perforated face plate 9 to cool and dry the garment.

One of the primary advantages of this invention is the dual function performed by the steam in first passing through and heating the bed, after which it is utilized to produce the necessary suction to withdraw the steam, heat and moisture from a garment just pressed. In this way live hot steam is periodically supplied to the bed, which 90 avoids the possibility of a considerable amount of moisture of condensation accumulating in the heating chamber; and what slight condensation does accumulate therein, 95 is blown out during each drying and cooling operation.

Claims.

1. In a garment press, the combination of a pressing element having a perforated pressing surface and a heating chamber; a suction conduit in communication with the pressing surface of said element; and means for passing a heating medium to and 105 from said chamber.

through said chamber and through the action of the heating medium discharged from said chamber effecting a suction in the conduit.

5. 2. In a garment press, the combination of a pressing element having a perforated pressing surface and a heating chamber; a suction conduit in communication with the pressing surface of said element; and means for 10 passing steam to and through said chamber and through the action of the steam discharged from said chamber effecting a suction in the conduit.

3. An improvement in piping systems for 15 steam garment presses comprising a pipe to supply steam to heat one of the members of the press, a second pipe to convey the steam away from said member, a suction pipe joined with the second named pipe, and an 20 ejector tube arranged at the juncture of the second named pipe and suction pipe to produce a suction through the press, where-

by heat and moisture are withdrawn from the garment.

4. A piping system for steam garment 25 pressing machines comprising means to supply steam to circulate within and heat the pressing member of said machine, said pressing member having a perforated pressing surface, a discharge pipe to carry the 30 steam away from the pressing member, a valve included in the discharge pipe, an ejector included in the discharge pipe, and a suction pipe connecting an ejector and pressing member, whereby when the valve is opened 35 to discharge steam from the pressing member through the ejector and suction will be induced through the aforesaid discharge pipe and perforated pressing surface.

In witness whereof I have hereunto set 40 my hand this 27 day of January, 1921, at Syracuse, county of Onondaga, State of New York.

P. EDUARD GELDHOF.
